Application September 21, 1937, Serial No. 164,910

15 Claims. (Cl. 158—28)

In a control system, for example for a fuel burning device, it is desirable to delay the restarting of the device for a period of time after cessation of operation of the device in order to 5 permit purging of gas from the furnace.

One of the objects of the present invention is to provide a control system, for example for a fuel burning device, in which upon cessation of 10 operation, a control circuit is rendered inoperative, for a timed period, and therefore cannot operate to restart the system during this timed period although there is a demand for operation of the device.

Such systems are of necessity provided with 15 safety mechanism which prevents the ingress of fuel into the furnace in the event of abnormal conditions such as the failure of combustion at the time or starting or after the fuel burning device has been operating. Usually an electrically 20 heated safety mechanism is employed in the system and it is desirable to maintain the mechanism heated during the entire operation of the burning device so that the same is effective immediately for rendering the device inoperative 25 in the event of an abnormal condition. It is also desirable to interrupt the ignition after a timed period so that ignition is furnished during a starting period only.

It is another object of the invention to utilize 30 the timer of the safety mechanism to control the ignition also and to also utilize this timer for delaying the restarting of the burning device, for a timed period, after cessation of operation of the device.

In carrying out the foregoing object, it is a 35 further object to provide a control system in which the control circuit, which is rendered inoperative upon cessation of operation of the burning device, is not rendered effective until the ignition circuit is rendered effective.

A still further object is to provide a control 40 system in which the electrically operated heater is in the control circuit and which control circuit is rendered inoperative upon cessation of operation of the burning device.

Further objects and advantages will be apparent from the following description, reference 45 being had to the accompanying drawings wherein preferred forms of embodiments of the present invention are clearly shown.

In the drawings:

Fig. 1 is a wiring diagram of one form of control system, the system being shown in the operating position, with the room thermostat in the cold or closed circuit position;

Fig. 2 is a view of the thermostat showing the same in its intermediate position;

Fig. 3 is a view similar to Fig. 2 showing the thermostat in the heated or open circuit position, and,

Fig. 4 is a wiring diagram of another form of control system, the system being shown in the operating position.

Referring to Fig. 1, the system is illustrated as controlling the operation of a conventional type 10 of oil burning device. The system, as shown, is operatively responsive to a thermostat 20, such as a room thermostat, which closes a low voltage secondary circuit when there is a demand for heat, to cause the oil burning device to operate, 15 and which opens the secondary circuit when that demand is satisfied. A transformer relay 24 is utilized as a means to supply low voltage current to the system and as a means for operating various control switches. The secondary or 20 starting circuit may be traced as follows: secondary coil 22 of transformer relay 24, wire 26, wire 28, contacts 30 and 32 and member 34 of thermostat 20, wire 36, resilient member 38, contacts 40 and 42 of time relay switch 44, heating 25 coil 46 and wire 48. Completion of the secondary circuit, by room thermostat 20, causes the transformer relay 24 to draw its armature 50 upwardly to close the associated switches 52 and 54. Closure of switch 54 energizes the motor and 30 ignition circuits, which will be explained in detail hereinafter. Closure of switch 52 completes a shunt circuit around contact 30 of the thermostat 20. This circuit may be traced from secondary coil 22, wire 26, switch 52, wire 56, thermostatic 35 metal 58, contacts 60, 32 and member 34 of thermostat 20, wire 36, resilient member 38, time delay switch 44, heating coil 46, and wire 48.

Thus it will be seen, that in order to start the 40 system, the thermostat 20 must be in the position shown in Fig. 1, wherein all three contacts are in engagement. After closure of the holding switch 52, the thermostat may deflect to the position shown in Fig. 2, wherein the contacts 32 and 60 are in engagement and the circuit through 45 contact 30 has been interrupted. This type of thermostat is well known in the art. The system will remain operative until the thermostat 20 is heated sufficiently to deflect to the position shown in Fig. 3, wherein all of the contacts 50 of the thermostat 20 are separated, at which instant the secondary circuit is deenergized to cause the transformer relay 24 to release the armature 50.

The high voltage primary circuit includes the

primary coil 62 of transformer relay 24, which is connected across the main line through a safety switch 64. The primary coil 62 is constantly energized while the safety switch 64 is in the closed circuit position. This circuit may be traced as follows: wire 66, to the primary coil 62, wire 68, safety switch 64, and wire 70. It will be noted that wires 66 and 70 connect to the line or current supply for the system.

10 The motor and ignition circuits for controlling the motor 72 and ignition device 74 are controlled by switch 54. The motor circuit may be traced as follows: wires 66 and 76, motor 72, wire 86, switch 54, wires 84 and 68, safety switch 64 and wire 70. The ignition circuit follows, wires 66, 76 and 78, ignition switch 80, wire 82, ignition transformer primary 74, wires 88 and 86, switch 54, wires 84 and 68, safety switch 64 and wire 70. The ignition secondary circuit is shown at 20 89. It will be noted that the motor 72 and ignition primary 74 are connected in parallel and upon initiation of operation are responsive to the operation of switch 54 controlled by the transformer relay 24. The ignition primary 74 is subsequently deenergized by the opening of the ignition switch 80.

25 The motor 72, previously mentioned, is used to propel a fuel pump and an air pump, to supply fuel to the fuel burning device, which fuel is ignited by the ignition device.

The normal operation of the system may be explained as follows: when the thermostat calls for heat, the secondary circuit of the system is energized, to cause the transformer relay to 30 attract its armature 50 and close switches 52 and 54. Closure of switch 54 energizes motor 72 to cause fuel to be fed to the fuel burning device which fuel is ignited by the ignition device. Completion of the secondary control circuit also causes current to flow continuously through the heating coil 46 throughout operating periods of the fuel burning device. Coil 46 is disposed in intimate heat transfer relation to a U shaped bimetal thermostat 90 to cause the same to be deflected upwardly during the heating thereof. A shouldered pin 92, is disposed on the moving blade of the thermostat 90, the shoulder 94 of pin 92 being adapted to engage a pivotally mounted lever 96, which controls the ignition switch 80. After a predetermined period of heating of the thermostat 90, the same moves upwardly sufficiently to cause the shoulder 94 of pin 92 to engage the lever 96 and thus open the ignition switch 80. In this manner the ignition device is rendered inoperative, after a timed period of operation thereof. It is apparent that this operating period can be regulated to any period desired by moving lever 96 closer or farther away from the shoulder 94. The upper end 40 of the pin 92 abuts a second pivotally mounted lever 98. A combustion responsive control 100 is provided and is disposed to operate a latch 102 between stops 104 and 106, through a conventional slip clutch. Thus when the combustion chamber is cold the latch 102 is positioned against stop 104 but after combustion is established, the latch 102 is displaced by control 100 to engage stop 106. In this latter position the latch 102 will act as a stop for lever 98 when the same 45 is moved upwardly a sufficient distance by deflection of bimetal 90. This effectively prevents further upward movement of the lever 98 and also prevents further upward deflection of the bimetal 90.

The moving end of the bimetal 90 is disposed

to abut an operating lever 108 on the safety switch 64 and in the abutting position maintains the safety switch 64 in closed circuit position. Suitable means, such as a spring 110, are provided to bias the lever 108 to open circuit position of the switch 64 when the lever 108 is released by the bimetallic strip 90. It will be noted that the aforementioned action of combustion control 100 through latch 102 prevents the bimetal 90 from deflecting upwardly sufficiently to release the lever 108 and thus, when combustion is established within the system, the safety switch 64 is maintained closed.

During the upward deflection of bimetal 90 the contacts 40 and 42 of time delay switch 15 44 are maintained in engagement with each other due to the following action of the spring contact member 38, which carries the contact 40 and which is biased upwardly to cause the aforementioned following action.

Upon deenergization of the system due to opening of the thermostat 20, the secondary circuit of the transformer relay 24 is deenergized to cause armature 50 to drop downwardly. A pin or rod 112 depends from the armature 50 and is disposed to engage the resilient contact member 38, when the armature 50 drops downwardly, to depress the member 38 downwardly until the same engages stop 114. This action opens circuits the time delay switch 44 and the system 30 cannot be reenergized until bimetal 90 has cooled sufficiently to reengage contacts 40 and 42 of time delay switch 44. A pin 116 carried by lever 98 is also provided and is abutted by the armature 50 when the same drops downwardly to maintain the bimetal 90 in engagement with safety switch lever 108. This is necessary since the combustion control acts quite rapidly due to the slip clutch connection and displaces latch 102 so that the same does not engage lever 98 prior to the time 40 the bimetal 90 has cooled sufficiently to assure that it will not release the safety switch lever 108. Thus the armature 50 maintains the safety switch closed upon deenergization of the system and after the combustion control has cooled. 45

When combustion is not established within the system, upon initial starting thereof, the combustion control 100 is non-operative and therefore bimetal 90 is permitted to deflect sufficiently to release safety switch lever 108 which opens 50 switch 64 and deenergizes the system. A similar action occurs upon failure of combustion during the operating cycle of the system, wherein the control 100 displaces latch 102 out of engagement with lever 98 to allow bimetal 90, which 55 is heated by coil 46 to a temperature above the temperature necessary to release the lever 108, to move upwardly for causing the safety switch to be instantly open circuited. In either of the above mentioned exigencies, the safety switch 60 must be reset manually before the system can be restarted.

After cessation of operation of the system whether normal or in the event of power failure during an operating cycle of the system, even 65 if same is momentary, the armature 50 drops downwardly to cause the rod 112 to open circuit time delay switch 44 which renders the system incapable of reenergization until the thermostat 90 has cooled sufficiently to reengage the contacts 40 and 42 of the time delay switch 44. It will be noted that prior to the closure of the time delay switch 44, the ignition switch 80 is reclosed to assure that the ignition device 74 will be in readiness to operate when the system 70 75

is reenergized. This delay of restarting is timed, through thermostat 90, so that sufficient time elapses to permit purging of the furnace of gas and thereby insures against explosives.

5 Referring to Fig. 4, a similar system is shown with the exception that a two wire thermostat 120 is utilized in place of the three wire thermostat 20. In this system, the holding switch 52 can be eliminated and the secondary circuit may be 10 traced as follows: secondary 22, wire 26, contacts 122, 124 and bimetal 126 of the thermostat 120, wire 36, resilient member 38, time delay switch 44, heating coil 46 and wire 48. The operation of apparatus in this system is identical in every 15 respect to the operation of the apparatus as previously described in connection with Fig. 1.

It is apparent that certain advantages are present. Quick operation of the safety mechanism is insured because the heating coil therefor 20 is continuously energized during the operation of the fuel burning device. In the event of combustion failure, the thermostat immediately will open the safety switch 64 as soon as the combustion control releases lever 98. To have the 25 heater 46 operate continuously during the operation of the burning device necessitates a continuously energized circuit therefor and in the event of temporary power failure, the circuit for the heater coil must be reenergized upon return 30 of the electrical power, in order to insure the safety operation of the system. By the present invention, safe operation is insured under all conditions. The heater 46 for the safety mechanism is in series with the starting circuit and 35 the arrangement is such that the starting circuit cannot be reenergized for a timed period after cessation of operation of the burning device. Also the ignition circuit is rendered effective at 40 80 before the starting circuit is energized. In this manner, the fuel supply motor 72 cannot be restarted until ignition is present and the furnace is purged of gas.

While the forms of embodiment of the present 45 invention as herein disclosed constitutes preferred forms, it is to be understood that other forms might be adapted, all coming within the scope of the claims which follow:

We claim:

1. A control system for a fuel burning device 50 comprising in combination; electrically operated means for controlling the fuel burning device; an electrical circuit for rendering said means operative including a switch; means responsive to de-energization of the electrically operated means 55 for opening said switch; and thermostatic means operable after a predetermined time for closing said switch.

2. A control system for a fuel burning device 60 comprising in combination; electrically operated means for controlling the fuel burning device; an electrical circuit for rendering said means operative including a switch; means responsive to de-energization of the electrically operated means 65 for opening said switch; and timing means operable after a predetermined time for closing said switch.

3. A control system for a fuel burning device 70 comprising in combination; electrically operated means for controlling the fuel burning device; an electrical circuit for rendering said means operative including a switch; electrically operated 75 thermostatic means; means for energizing the thermostatic means during operation of the fuel burning device; a safety switch actuated by the thermostatic means for rendering the circuit in-

operative a predetermined time after energization of the circuit; means responsive to the establishment of combustion for preventing operation of the safety switch; and means responsive to de-energization of the electrically operated means 5 for opening the first mentioned switch; said thermostatic means for reclosing said first mentioned switch a predetermined time after the opening thereof.

4. A control system for a fuel burning device 10 comprising in combination, electrically operated means for controlling the fuel burning device; an electrical circuit for rendering said means operative including a switch; electrically operated timing means; a safety switch actuated by the 15 timing means for deenergizing the circuit a predetermined time after energization thereof; means responsive to the establishment of combustion for preventing operation of the safety switch; means responsive to de-energization of the electrical 20 means for opening the first mentioned switch; said timing means being operable to reclose said first mentioned switch a predetermined time after the opening thereof.

5. A control system for a fuel burning device 25 comprising, electrically operated means for causing starting of said device; an electric circuit for rendering said means operative; temperature responsive means adapted to be heated when the fuel burning device is started; a switch associated with said temperature responsive means and connected in said circuit, means for biasing said switch closed during the operating period of the fuel burning device; and means rendered effective 30 upon deenergization of the electrically operated means for opening the switch for causing said circuit to be non-operative, said temperature responsive means being operative to close the switch.

6. A control system for a fuel burning device 40 comprising electrically operated means for causing starting of said device; an electrical circuit for rendering said means operative; an electrically heated thermostat adapted to be energized when the fuel burning device is started; a switch 45 adapted to be operated by said thermostat and connected in said circuit; means for biasing said switch closed during the operating period of the fuel burning device; and means rendered effective 50 upon deenergization of the electrically operated means for opening said switch for causing said circuit to be non-operative, said thermostat being operative to close the switch a predetermined time after deenergization of the thermostat. 55

7. A control system for a fuel burning device comprising, electrically operated means for causing starting of said device; an electrical circuit for rendering said means operative; an electrically heated thermostat adapted to be energized when the fuel burning device is started; a switch adapted to be operated by said thermostat and connected in said circuit; means for biasing said switch closed during the operating period of the fuel burning device; ignition means for igniting the fuel; a controller for the ignition means, said electrically heated thermostat being adapted to actuate said controller subsequent to the starting of the fuel burning device and after a predetermined period of operation of the ignition means; and means rendered effective upon deenergization of the electrically operated means for opening said switch for causing said circuit to be non-operative a said thermostat being operative to 70 75

close the switch a predetermined time after opening thereof.

8. A control system for a fuel burning device comprising, electrically operated means for causing starting of said device; an electrical circuit for rendering said means operative; an electrically heated thermostat adapted to be energized when the fuel burning device is started; a switch adapted to be opened by said thermostat and

- 5 connected in said circuit; means for biasing said switch closed during the operating period of the fuel burning device; ignition means for igniting the fuel; a controller for the ignition means, said electrically heated thermostat being adapted to 10 actuate said controller subsequent to the starting of the fuel burning device and after a predetermined period of operation of the ignition means; a safety switch operable to stop the fuel burning device and adapted to be actuated by the electrically heated thermostat subsequent to the operation of the ignition controller; means responsive to the establishment of combustion for preventing the safety switch from stopping the fuel burning device; and means rendered effective upon deenergization of the electrically operated means for opening said first mentioned switch for causing said circuit to be non-operative until said thermostat operates to close the first mentioned switch.

- 15 30 9. A control system for a fuel burning device comprising, electrically operated means for causing the starting of said device; an electric circuit for rendering said means operative; a switch connected in said circuit; means for biasing said switch closed during the operating period of the fuel burning device; ignition means for igniting the fuel; a switch for controlling the operation of the ignition means; an electrically heated thermostat adapted to be energized when 20 the fuel burning device is started and to be continuously heated during the operating period of the fuel burning device, said thermostat being adapted after a predetermined period of heating thereof to actuate said ignition switch; and means rendered effective upon deenergization of the electrically operated means for operating said first mentioned switch for causing said circuit to be non-operative; and means actuated by said thermostat during cooling thereof to close the 25 50 first mentioned switch.

10. A control system for a fuel burning device comprising, electrically operated means for causing the starting of said device; an electric circuit for rendering said means operative; a switch connected in said circuit; means for biasing said switch closed during the operating period of the fuel burning device; ignition means for igniting the fuel; a switch for controlling the operation of the ignition means; a safety switch for deenergizing the fuel burning device; an electrically heated thermostat adapted to be energized when the fuel burning device is started and continuously heated during operating periods of the fuel burning device; means interconnecting the thermostat and the three mentioned switches, said thermostat being adapted to successively open the ignition switch and the safety switch after a predetermined period of operation of the fuel burning device; means responsive to the establishment of combustion for preventing opening of the safety switch; and means rendered effective upon deenergization of the electrically operated means for opening said first mentioned switch, said mentioned switch being closed by the thermostat on cooling of the thermostat.

11. A control system for a fuel burning device comprising in combination, electrically operated means for controlling said fuel burning device; a circuit for said means; a thermostatic device adapted to be electrically heated continuously during operating periods of the fuel burning device, and in said circuit, and including a thermostatic contact member which is deflected by the heat; a following contact disposed to engage the thermostatic contact member during deflection thereof; and means operated by the electrically operated means upon deenergization of the same for separating the following contact and the thermostatic contact member for interposing a delay between successive energizations of the electrical- 15 ly operated means.

12. A control system for a fuel burning device comprising in combination; electrically operated means for controlling said fuel burning device; a circuit for said means; ignition means for igniting the fuel; an ignition switch for controlling the operation of the ignition means; a thermostatic device adapted to be electrically heated during operating periods of the fuel burning device and in said circuit, including a thermostatic contact member which is deflected by the heat; a resiliently mounted contact disposed to follow the movement of the thermostatic contact member, said thermostatic contact member being adapted to open said ignition switch after a predetermined period of heating of the thermostatic member; and means operated by the electrically operated means upon deenergization of the same for separating said resiliently mounted contact and said thermostatic contact member for interposing a delay between successive energizations of the fuel burning device.

13. A control system for a fuel burning device comprising in combination, electrically operated means for controlling said fuel burning device; a circuit for said means; ignition means for igniting the fuel; an ignition switch for controlling the operation of the ignition means; a safety switch operable to deenergize the electrically operated means; a thermostatic switch device in said circuit and adapted to be electrically heated during operating periods of the fuel burning device, including a thermostatic contact member which is deflected by the heat; a resiliently mounted contact disposed to follow the movement of the thermostatic control member, said thermostatic switch device being adapted to actuate first said ignition switch and then said safety switch after a predetermined period of heating of the thermostatic member; means responsive to combustion for preventing the safety switch from deenergizing the electrically operated means; and means operated by the electrically operated means upon deenergization of the same for separating said resiliently mounted contact and said thermostatic member for interposing a delay between successive energizations of the fuel burning device.

14. A control system for a fuel burning device comprising in combination, electrically operated means for controlling said fuel burning device; a control circuit for said electrically operated means; a thermostatically operated switch in series with said electrically operated means, said switch comprising a movable contact member and a thermostat adapted to actuate said contact, and a second movable contact member; means for heating said thermostat in response to energization of said fuel burning device; means for biasing the second contact member against the

- first mentioned contact member; and means actuated in response to deenergization of said electrically operated means for biasing said second contact member to a position away from the first mentioned contact member.
5. 15. In a control system for an electrically operated fuel burning device, a magnetically operated switch means for controlling said device; a circuit for controlling the operation of said mag-
- netically operated switch means, a switch in series with said magnetic means; means for opening said switch in response to deenergization of said magnetic means; and means for closing said switch within a predetermined time period after the deenergization of said fuel burning device.

ELDON D. RANEY.

CERTIFICATE OF CORRECTION.

Patent No. 2,180,067.

November 14, 1939.

ELDON D. RANEY, ET AL.

It is hereby certified that error appears in the printed specification of the above numbered patent requiring correction as follows: Page 1, second column, line 25, for the word "relay" read --delay--; line 32, for "82" read --52--; page 3, second column, line 75, claim 7, strike out "a" before "said" and insert instead a comma; and that the said Letters Patent should be read with this correction therein that the same may conform to the record of the case in the Patent Office.

Signed and sealed this 20th day of May, A. D. 1941.

(Seal)

Henry Van Arsdale,
Acting Commissioner of Patents.
